UNITED STATES PATENT OFFICE.

MAURICE H. STRONG, OF CINCINNATI, OHIO.

POULTRY WATER-CAN.

SPECIFICATION forming part of Letters Patent No. 331,097, dated November 24, 1885.

Application filed November 4, 1884. Serial No. 147,149. (No model.)

To all whom it may concern:

Be it known that I, MAURICE H. STRONG, of Cincinnati, Hamilton county, Ohio, have invented a new and Improved Poultry Water-
5 Can, of which the following is a full, clear, and exact description.

The object of my invention is to provide a new and improved poultry water-can, which is so constructed that the fowls cannot soil the
10 water by stepping into it or scratching dirt into it, and which can is constructed as a fountain to supply the water to the trough as rapidly as it may require.

The invention consists in the construction
15 and arrangement of parts, as will be herein-after fully described and claimed.

The neck on the can and flange in the cup are provided with apertures, through which the water can pass from the can into the circular or annular trough formed in the cup.

Reference is to be had to the accompanying drawings, forming part of this specification, in which similar letters of reference indicate corresponding parts in all the figures.

25 Figure 1 is a cross-sectional view of my improved poultry water-can. Fig. 2 is a sectional plan view on the line *x x*, Fig. 1, and Figs. 3 and 4 show the joint for uniting the can and cup.

30 The can A, which is open at the bottom, is provided at its top with a screw-neck, B, on which a screw-cap, C, is secured to close the top of the can, a packing-ring being interposed between the top of the can and the
35 flange of the screw-cap for the purpose of forming a close and tight joint. A bail, D, is secured to the can near its top.

The can preferably increases in diameter from the top to within a short distance from
40 the bottom, and is then contracted.

On the lower end of the can a downwardly-projecting neck, E, is formed, and on a flat cup, F, an upwardly-projecting flange, G, is

formed, in which the neck E fits closely, and which flange G forms an annular trough, H, 45 in the cup F. L-shaped slots J are provided in the top part of the flange G, from the top edge down, and pins K project from the neck E. Apertures L are formed in the neck E and flange G, which coincide when the neck E 50 is locked in the flange G.

To fill the can, the neck E is placed in the flange G, the pins K passing into the slots J, to hold the cup F to the can. The cap C is unscrewed and the can is immersed in water, 55 the water passing through the apertures L into the can and gradually filling the same. When the can is filled as much as desired, the cap C is screwed on and the can removed from the water.

The level of the water in the trough H is slightly above the apertures L, and when the water-level sinks below the apertures L fresh water flows from the can, but only until the apertures L are closed again.

60 The several parts can easily be taken apart for scouring and cleaning them.

The can can be carried about very easily, and all waste of water is prevented.

Having thus described my invention, I claim 70 as new and desire to secure by Letters Patent—

1. The combination, with the can A, having the neck E, of the cup F, having the flange G, the neck E and flange G having apertures which can be adjusted to coincide, substantially as herein shown and described.

2. The combination, with the can A, having the neck E, provided with apertures L and pins K, of the cup F, having the upwardly-projecting flange G, provided with L-shaped slots J and apertures L, substantially as herein shown and described.

MAURICE H. STRONG.
